UNITED STATES PATENT OFFICE.

HERMAN HENRY GERDES, OF ALVARADO, TEXAS.

TIME-CONTROLLING MECHANISM.

1,238,282.

Specification of Letters Patent. Patented Aug. 28, 1917.

Application filed June 29, 1916. Serial No. 106,678.

To all whom it may concern:

Be it known that I, HERMAN HENRY GERDES, a citizen of the United States, residing at Alvarado, in the county of Johnson and State of Texas, have invented certain new and useful Improvements in Time-Controlling Mechanism; and I do declare the following to be a full, clear, and exact description of the invention, such as will 10 enable others skilled in the art to which it appertains to make and use the same.

This invention relates to a time controlling mechanism designed more particularly for the automatic operation of electric 15 switches, circuit closers, and the like.

An object of the invention is to provide a time controlling mechanism of this character which may be used in connection with an ordinary alarm clock to intermittently operate 20 the electric switch or other movable member at pre-determined intervals.

Another object of the invention is to improve upon devices of this general character by the provision of a simple, strong, durable and inexpensive construction, and a device 25 which will be efficient and reliable in operation and well adapted to the purpose designed.

With these and numerous other objects in 30 view, the invention consists of certain novel features of construction and the combination and arrangement of parts as will be herein-after fully described and claimed.

In the accompanying drawings forming a 35 part of the specification, and in which similar reference characters designate like parts throughout the several views,

Figure 1 is a front elevation of a device 40 constructed in accordance with this invention, the base member of the same being here shown in cross section;

Fig. 2 is a top plan view of the same;

Fig. 3 is a vertical sectional view taken on the plane of the line 3—3 of Fig. 2;

Fig. 4 is a transverse vertical section taken 45 on the plane of the line 4—4 of Fig. 2;

Fig. 5 is a similar view taken on the plane of the line 5—5 of Fig. 1.

Fig. 6 is a front elevation of the one day 50 dial, the central portion of which is broken away to show the rear end operatively connected with the same;

Fig. 7 is a similar view of the eight day dial;

Fig. 8 is a perspective view of a portion 55

of the rear side of one of the dials, showing more particularly the foldable fingers carried by the same;

Fig. 9 is a detail perspective view illustrating the construction of the rock shaft, 60 and

Fig. 10 is an enlarged detail sectional view taken on the plane indicated by the line 10—10 of Fig. 1.

In the embodiment illustrated, the reference character 1 designates a horizontal table or base member on which the device to be hereinafter described is supported, and being provided at one of its ends with an upwardly extending flange or end wall 2. 65 Fixed to the end wall 2 is an electric knife switch 3 of the usual construction, and having a connecting element 4 in form of a pitman interposed between the same and operating means which is now to be described. 70 It is to be understood, however, that the switch 3 may be substituted by any form of intermittently operable movable member.

Secured to the horizontal table or member 1 in any suitable manner and at a point 80 spaced from the end wall 2 is a casing, preferably composed of a pair of upright plates 5 spaced a suitable distance apart by means of horizontal bars 6. Extending transversely between the side plates 5 and journaled in suitable bearings or openings in the same is a main shaft 7 on which is mounted in the usual manner a coil spring 7', and a ratchet wheel 8, the latter being engaged with a spring pressed pawl 9 to prevent 90 retrograde movement of said shaft. One end of the shaft extends beyond the outer side of the plates 5 and is provided with a thumb-piece or handle to be used when it is desired to wind the spring 7'. Fixed or 95 keyed in the usual manner to the barrel 7" of the spring 7' is a large gear wheel 10 and a smaller gear 11, the latter meshing with a gear 12 fixed to a shaft 13 which extends transversely between the plates 5 and being 100 revolvably mounted in suitable bearings therein. The gear 10 meshes with a pinion 14 carried by a shaft 15, which is similarly mounted between the side plates. This shaft 15 also carries a comparatively large gear 105 16 which meshes with a pinion 17 carried by a shaft 18 having fixed thereto a gear 19. The gear 19 in turn meshes with a pinion 20 mounted on a shaft 21, to which is also mounted a large gear 22, the latter being in 110

operative engagement with a pinion 23 carried by a shaft 24. This mechanism comprises a spring motor and the preferred means for imparting an intermittent movement to the switch 3.

- 5 Fixed to one end of the shaft 13 is a rotary member 25, here shown as being circular in configuration, and being provided with suitable means for pivotal attachment 10 to the other end of the pitman or connecting element 4. This member 25 is provided on its periphery with a pair of diametrically opposite stops 26 to be hereinafter fully described. By this construction it may be seen 15 that when the spring motor is allowed to operate the member 25 will revolve, thus giving the pitman 4 a to and fro motion, and thereby opening and closing or imparting an intermittent movement to the 20 switch 3.

The shaft 24 is provided on one of its ends on the exterior side of one of the plates 5 with a small solid friction wheel 27 which, in conjunction with a member or bar 28, 25 having a spring 27', forms a braking means for the motor, whereby the latter is stopped and started at pre-determined intervals. This member 28 is securely fixed to one of the plates 5 at one of its ends, and has its 30 other end disposed adjacent the periphery of the rotating member 25, whereby it may be engaged with one of the stops 26.

The member 28 is provided with a resilient portion 28' intermediate of its ends adjacent the friction wheel 27 as clearly shown by the drawings. When one of the stops 26 is engaged with the last referred to end of the member 28, the latter will be bent upwardly at its resilient portion 28'. This 40 causes the spring 27' to bear upon the friction wheel 27 with sufficient pressure to maintain the motor at the condition of rest.

The means for operating the braking means comprises a cam 29, which is mounted 45 between suitable brackets 30 fixed to one of the plates 5, and being provided at its opposite ends with an arm 31 and a stop 31'. The free end of the arm 31 is pivotally connected to a link 32', the other end of the 50 latter being in turn similarly connected to the free end of a pivoted lever 33, having a pin 34 extending laterally from one of its sides and at the free end thereof. The stop 31' is spaced a very slight distance below the lower side of the member 28 when the parts are in their normal positions as clearly shown in Fig. 1 of the drawings. By this construction it may be seen that when the lever 33 is moved in the direction 55 60 toward the cam 29, the latter will be brought into engagement with the member 28, thereby moving said member 28 in a direction perpendicular to the plate 5 and out of engagement with the pin 26. Owing to the 65 fact that the stop 31' is spaced a very slight

distance below the lower side of the member 28, the latter will then spring downwardly into engagement with said stop 31', this movement, however, being so slight as to not take away an appreciable amount of 75 pressure from the friction wheel 27. When the finger 45 passes out of engagement with the pin 34, the lever 33 is released, the resiliency of the member 28 moving the same, together with the cam 29 into their normal 75 positions, and thus the stop 31' is moved out of engagement with the member 28, the latter, by virtue of its spring portion 28', falling on the other side of the pin 26 with which it was just engaged and moving the 80 spring 27' out of contact with the friction wheel 27. It is to be here noted that the inner side of the free end of the member 28 and the outer sides of the pins 26 are oppositely beveled in order to cause said member 28 to fall on the other side of the pin 26 with which it was just engaged when said member is allowed to spring back toward the plate 5 and have its free end disposed in the path of the next pin 26. As the member 25 revolves, the last mentioned pin 26 is moved through 180 degrees and engages the member 28, thereby causing the latter to bend at its resilient portion and engage the friction wheel 27 to gradually but effectively stop the motor. The momentum of the solid wheel 27 and the other rapidly rotating members of the motor prevents the latter from being stopped until the member 28 is moved to its normal position slightly 100 above the stop 31'. This, as will be readily understood, assists the beveled sides of the pins 26 and the free end of the member 28 in placing the latter on the proper side of the pins 26 when said member 28 is allowed 105 to spring back toward the plate 5.

For actuating the cam 29 and the lever 33, the following means is preferably to be employed. This means comprises a rotating dial 35 arranged on the outer side of one of the plates 5. Extending through the central portion of the dial 35 is a comparatively short shaft 36, to the inner end of which is fixed a pinion 37 meshing with a gear wheel 38 fixed to a pinion 39, the latter being rev- 110 olubly mounted in any convenient manner to the adjacent plate 5. This pinion 39 in turn meshes with a gear wheel 40 operatively connected in a convenient manner with the dial 35, whereby said dial may be rotated 115 when the shaft 36 is rotated, and at a speed in proportion to the speed of the shaft depending upon the ratio of the gears. The outer or free end of the shaft 36 is provided with a suitable means for detachable connection to a rotating member here shown as the setting key 41 of an ordinary alarm clock C.

The last referred to means is preferably composed of an additional shaft 42 arranged 120

substantially in alignment with the shaft 36, and having its inner end connected to the outer free end of the shaft 36 by means of a universal joint 43. The other end of the 5 shaft 42 is provided with a spring clamp 44, whereby said shaft 42 may be quickly and detachably connected to the setting key 41 of the alarm clock.

The dial 35 is provided with a plurality of 10 projections in the form of fingers 45. These fingers 45 are pivotally connected at their inner ends to one side of the dial on a circle substantially concentric with the central axis thereof. By this construction it may be seen 15 that a number of fingers may be moved to their uppermost position, and into engagement with stops 46 carried by said dial, whereupon they extend substantially radially from the periphery of the latter and 20 are positioned so as to engage the pin 34 carried by the lever 33 when the dial is rotated.

In Figs. 1 and 6 of the drawings, the dial 35 is graduated around its outer edge with 25 figures running from 1 to 12 to correspond with the graduations on the dial of an ordinary clock. This is the one day dial, and is adapted to rotate twice during twenty four hours. The form of dial shown in Fig. 30 9 of the drawings is an eight day dial, it being provided with two sets of figures running from 1 to 12 to represent the hours of both day and night. Obviously when this form of dial is used the ratio of the gears 35 operatively connected with the same is changed so as to rotate the dial at the desired speed.

In operation of the device the shaft 42 is connected in the manner described to the 40 clock so as to be actuated by the same. The fingers 45 of the desired hours are moved into their extended positions, whereby when the dial is moved they will come into contact with the pin 34 and operate the lever 33 45 so as to actuate the cam 29, and thereby cause the braking means for the motor to be released. This obviously allows the motor to impart the desired movement to the switch 3. The motor will be stopped when 50 the other stop 26 is moved into engagement with the free end of the member 28 as hereinbefore described.

By this construction and arrangement of parts it may be seen that a very efficient device has been provided for intermittently operating a movable member at pre-determined 55 intervals. The mechanism is designed more particularly to be employed with the switch 3 for use in lighting and extinguishing the lights in show windows and the like, but it is to be understood numerous other uses and purposes may be allotted to this construction.

The construction herein shown and described is preferably the one to be used, but

it is to be understood that it may be changed to suit the emergencies of any particular case without departing from the spirit and scope of the invention as defined in the appended claims.

70

I claim as my invention:—

1. In a device of the class described, the combination with a movable member, a spring motor, a rotating member operated by said motor and having a stop thereon, 75 and means operatively connecting said movable member with said rotating member; of a friction wheel actuated by said motor, a braking member movable in two directions disposed in the path of said stop and normally engaged by the latter to maintain it normally in engagement with said friction wheel, means for moving said braking member in one direction out of engagement with said stop, thereby allowing it to move in a second direction out of engagement with said friction wheel, and a constantly rotating dial provided with means for intermittently operating the last named means.

2. In a device of the class described, the combination with a movable member, a spring motor, a rotating member operated by said motor and having a stop thereon, and means operatively connecting said movable member with said rotating member; of a friction wheel actuated by said motor, a resilient braking member fixed at one of its ends and movable in two directions, the other end of said braking member being disposed in the path of said stop and normally 100 engaged by the same, whereby the intermediate portion of said braking member is normally held in engagement with said friction wheel, means for moving said braking member in one direction out of engagement with said stop, thereby allowing it to spring in a second direction out of engagement with said friction wheel, and a constantly rotating dial provided with means for intermittently operating the last named means.

3. In a device of the class described, the combination with a movable member, a spring motor, a rotating member operated by said motor and having a stop thereon, and means operatively connecting said movable member with said rotating member; of a friction wheel actuated by said motor, a resilient braking member fixed at one of its ends and movable in two directions, the other end of said braking member being disposed in the path of said stop and normally engaged by the same, whereby the intermediate portion of said braking member is normally held in engagement with said friction wheel, a cam engaging the last mentioned end of said braking member for moving the same in one direction out of engagement with said stop, thereby allowing it to spring in a second direction out of engagement with said friction wheel, and a con-

stantly rotating dial provided with means for intermittently operating the last named means.

4. In a device of the class described the combination with a movable member, a spring motor, and means operatively connecting said movable member with said motor; of a friction wheel actuated by said motor, braking means normally in engagement with said friction wheel for maintaining said motor normally at rest, and including a pivotally mounted lever, a constantly rotating dial, and a plurality of fingers pivotally mounted at one of their ends to

one side of said dial on a circle concentric 15 with the axis of the latter, said fingers being adapted to extend radially and beyond the periphery of said dial for engagement with said lever to throw said braking member out of engagement with said friction 20 wheel.

In testimony whereof I have hereunto set my hand in presence of two subscribing witnesses.

HERMAN HENRY GERDES.
